UNITED STATES PATENT OFFICE

JENS CARL DITLEVSEN, OF ANTIOCH, CALIFORNIA

DESIGN FOR A FLYING TOP

Application filed July 21, 1930. Serial No. 36,424. Term of patent 3½ years.

To all whom it may concern:

Be it known that I, JENS C. DITLEVSEN, a subject of the Kingdom of Denmark, residing at Antioch, in the county of Contra Costa and State of California, have invented a new, original, and ornamental Design for a Flying Top, of which the following is a specification, reference being had to the accompanying drawing, forming part thereof, in which—

Fig. 1 is a perspective view of a flying top showing my new design, and Fig. 2 is a side elevation of the same.

The dominating features of the design are the laterally projecting extensions for simulating airplane propeller blades.

I claim:

The ornamental design for a flying top, substantially as shown and described.

JENS CARL DITLEVSEN.
